(57) **CLAIM**

The ornamental design for a notebook computer, as shown and described.

DESCRIPTION

FIG. 1 is a front perspective view of a notebook computer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof;

FIG. 9 is an enlarged view of the portion 9 delineated in FIG. 3; and,

FIG. 10 is an enlarged view of the portion 10 delineated in FIG. 3.

The broken lines illustrating portions of the notebook computer form no part of the claimed design. The dot-dash broken lines encircling enlarged portions of the claimed design form no part of the claimed design.

1 Claim, 8 Drawing Sheets
